UNITED STATES PATENT OFFICE.

REGINALD J. KOSTER, OF NEW YORK, N. Y., ASSIGNOR OF ONE-HALF TO FRED. E. BRIGHT, OF NEW YORK, N. Y.

SPARKING MECHANISM FOR INTERNAL-COMBUSTION ENGINES.

Application filed May 28, 1921. Serial No. 473,252.

To all whom it may concern:

Be it known that I, REGINALD J. KOSTER, a subject of the King of Great Britain and Ireland, residing at New York, in the county 5 of New York and State of New York, have invented certain new and useful Improvements in Sparking Mechanism for Internal-Combustion Engines, of which the following is a specification, reference being had there- 10 in to the accompanying drawing.

This invention relates to spark plugs employed in internal combustion engines to ignite the explosive charge, the objects of the invention being to provide a device of 15 simple construction which will be effective in operation and economical in current consumption, and in which the sparking surfaces will be maintained in clean condition free from the accumulation of carbon. 20 With these and other objects in view, my invention consists mainly in a spark plug embodying a single electrode which is designed to cooperate, in producing the spark, with an extended surface forming a part of 25 the engine structure, whereby the current will have a path of maximum conductivity free from any breaks or joints, and whereby the sparking surfaces will be maintained in clean unfouled condition.

30 In the accompanying drawings:

Fig. 1 is a vertical section through the upper end of the engine structure of an internal combustion engine, having my invention embodied therein.

35 Fig. 2 is a horizontal sectional plan view on the line *a—a* of Fig. 1.

Referring to the drawings:

1 designates the engine structure of an internal combustion engine, said structure 40 being provided with a power cylinder 2 in which a piston 2^a slides. The upper end of the cylinder is closed by a head 3 which projects laterally beyond the cylinder over a flat extended portion 4 integral with the 45 engine structure, thereby forming a valve or combustion chamber 5, the bottom of which is formed with an inlet port and with an exhaust port controlled respectively by valves 8 and 9.

50 The spark plug, designated by the numeral 10, comprises in the present instance a cylindrical sleeve 11 threaded exteriorly and screwed in place in a threaded opening in the cylinder head centrally over the flat

extended surface of the bottom 4 of the 55 valve chamber at a point between the two valve openings. An insulating body 12 is fixed within the sleeve 11 and is provided with an opening therethrough to receive the electrode 13 of the spark plug, which insulating body may be of any suitable insulating material such as porcelain, fiber and the like, the lower end of said body projecting below the end of the sleeve and being rounded as at 12^a. The electrode 13 is 60 straight throughout its extent and is threaded exteriorly as at 13^a and extends at both ends beyond the insulating body, its lower end being adapted to cooperate with the flat extended bottom of the valve chamber in forming the spark, which bottom thus forms in effect a second electrode, between which and the end of the electrode 13, the spark is formed. At its upper end the insulating body has a head 15 applied to it 65 containing a central threaded opening in which the electrode is screwed, and the upper portion of the head is slotted to form flexible sections adapted to be clamped tightly against the threaded portion of the 70 electrode to hold it in its adjusted position. This head is tapered and threaded externally, and a lock nut 16 is provided with a tapered threaded opening to screw on the head and clamp the flexible sections thereof 75 against the electrode. This tapered opening in the nut is continued on through the nut in the form of a cylindrical unthreaded opening 16^a which surrounds the threaded portion of the electrode without engaging it, 80 so as not to disturb the adjusted position of the electrode when the nut is screwed up to lock the same. By reason of the construction described, the electrode 13 may be adjusted in the spark plug structure so as 85 to establish and maintain a proper distance between its sparking end and the flat sparking surface on the bottom of the valve chamber, such adjustment being effected by turning the same by means of a knurled head 14, after first unscrewing the locking nut 16; and when the proper adjustment has 90 been effected, the locking nut is again screwed up so as to clamp the sections of the head 15 against the threaded portion of 95 the electrode.

One of the terminals of the sparking circuit will be connected as usual to the elec-

trode 13, while the other terminal will be connected as usual with the engine structure, and the electric circuit will have an uninterrupted path through the electrode 13 and through the engine structure to the point where the spark is formed, and as the path thus constituted by the electrode and engine structure will be free from breaks or joints, the circuit will possess a maximum degree of conductivity and will thereby prevent any loss or waste in the current and will insure a spark of maximum vitality and effectiveness.

It is found in actual practice that with the parts arranged as above described, in which the electrode of the spark plug cooperates with its sparking end with a flat extended surface on the engine structure as constituted by the flat bottom of the valve chamber, the sparking surfaces are maintained in a clean unfouled condition, free from the accumulation of carbon, the flat surface on the bottom of the valve chamber where it surrounds the end of the electrode 13, and where the formation of the spark takes place, being for a considerable area bright and clean and wholly free from soot or carbon.

It will be observed that the extended surface on the engine structure with which the electrode 13 cooperates in producing the spark, is in free and open communication with the interior of the cylinder and is exposed and open to the free flow of the gases, and is not surrounded by any parts or projections which would act to pocket and confine the gases around the active spark producing surfaces and thereby favor the collection and accumulation of carbon.

While in the accompanying drawings and in the foregoing description the electrode is shown as cooperating in forming the spark, with the flat bottom of the valve chamber of the engine structure, it is manifest that the electrode may be applied in other positions with good results; provided that in such other positions the electrode constituted by the engine structure will consist of some extended portion of the same, as distinguished from a limited surface, such for instance as would be constituted by a pointed projection of said engine structure, the essence of the invention in this respect residing in a sparking surface on the engine structure and of an extended area as distinguished from a projecting point or pocket or closely circumscribed surface. I am not prepared to state definitely and exactly the reasons why the cooperation of the electrode 13 with such a generally flat surface gives the advantages and results which in practice have been found to follow, and due to which the sparking surfaces are maintained in a clean unfouled condition. Suffice it to say that the advantages claimed have been

found to result from the arrangement described, and I believe myself to be the first to provide a spark plug with a single electrode and to apply the same at such a point or position on the engine structure that it will cooperate, in forming the spark, with an extended surface on said engine structure.

In establishing a proper interval between the end of the electrode 13 and the bottom of the valve chamber, the electrode is first screwed down so as to contact with the bottom, and it is then unscrewed a partial turn by means of the head 14, which head may be provided with an indicating mark 14^a to enable the head to be turned the proper distance to secure the desired interval of separation. With the threads on the electrode of a known predetermined pitch, any desired interval of separation may be readily determined by the degree of movement of the indicating mark from its initial position with the electrode in contact with the bottom of the valve chamber. In this way a very accurate adjustment of the electrode may be effected from the outside and without the necessity of removing the plug structure as a whole from the engine structure. The feature of the adjustability of the electrode as above described is of particular importance and advantage in connection with engines having a number of power cylinders, since it enables the electrodes of the individual cylinders to be adjusted independently of each other to vary the sparking intervals, according to the variation of compression in the different cylinders, and in accordance with other changing conditions. The adjustment of the electrode for this purpose may be effected while the engine is in operation, and in these circumstances, in order to prevent any shock from the current, a portable cap A of flexible rubber or other insulating material may be carried by the operator and applied to the knurled head 14 of the electrode when the adjustment is to be effected.

While I have shown and described in carrying out my invention, the use of a spark plug in which the electrode is adjustable from the outside, and while this particular feature of the spark plug possesses the advantages above enumerated, it is not necessary nor essential to my invention, and per se forms no part of my invention, as it is manifest that a spark plug with a non-adjustable or fixed electrode could be employed in cooperative relation to an extended portion of the engine structure in carrying out my invention, with all the advantages resulting from such cooperation, in so far as the high conductivity of the current path and the ability to maintain the sparking surfaces in clean unfouled and effective condition for the production of a spark of the maximum vitality, are concerned.

In the foregoing description and accom-

panying drawings I have set forth my invention in the particular detailed form and relation of the parts which in practice has been found to answer to a satisfactory degree the ends to be attained, but it will be manifest that these details may be variously changed and modified without departing from the spirit of the invention; and further it will be understood that the invention is not limited to any particular form or construction of the parts except in so far as such limitations are specified in the claims.

Having thus described my invention, what I claim is:

1. In an internal combustion engine, and in combination with the engine structure provided with a power cylinder and with a valve chamber in free and permanent communication with the cylinder, said valve chamber having a flat fixed bottom portion, and a sparking electrode sustained by the engine structure with its end in cooperative

sparkling relation to said flat portion of the valve chamber.

2. In an internal combustion engine, and in combination with the engine structure provided with a power cylinder and with a communicating valve chamber having inlet and exhaust valves in the bottom thereof, a sparking electrode sustained by the engine structure with its end in cooperative relation with the bottom of the valve chamber at a point thereof between the two valves.

3. In an internal combustion engine, and in combination with the engine structure provided with a power cylinder and with a valve chamber, said valve chamber having an extended fixed bottom portion, a sparking electrode sustained by the engine structure and having its end in cooperative relation to the bottom of the valve chamber.

In testimony whereof, I have affixed my signature hereto.

REGINALD J. KOSTER.
